UNITED STATES PATENT OFFICE.

WILLIAM F. SCHWEIGER AND WESLEY J. BALKWILL, OF ROCHESTER, NEW YORK,
ASSIGNORS TO MULTIPOST COMPANY, INCORPORATED, OF ROCHESTER, NEW YORK,
A CORPORATION OF NEW YORK.

ENVELOPE-MOISTENING MACHINE.

1,426,781.

Specification of Letters Patent. Patented Aug. 22, 1922.

Application filed January 31, 1920. Serial No. 355,326.

To all whom it may concern:

Be it known that we, WILLIAM F. SCHWEIGER and WESLEY J. BALKWILL, both citizens of the United States of America, residing at Rochester, in the county of Monroe and State of New York, have invented certain new and useful Improvements in Envelope-Moistening Machines, of which the following is a specification.

10 The invention relates to envelope sealing machinery, and its purpose is to afford mechanism which automatically and successively grips the lowermost one of a stack of envelopes, moistens the flap, and affixes it to the body of the envelope, these several operations being performed in a way to insure accuracy in positioning and feeding the envelope as well as speed of operation.

20 In a more particular aspect, one of the purposes of the improvement is the provision of novel mechanism that serves to prevent feeding of more than one envelope at a time, by retaining the stack against movement, with the exception of the lowermost envelope, devices being provided which operate with the envelopes immediately above the lowermost one, and prevent them from coming into cooperative relationship with the feeding means while the lowermost 30 envelope is being ejected.

Another purpose of the invention is to permit feeding an envelope with the flap extending downwardly beneath the envelope, with mechanism for properly moistening the flap 35 while in such lower position.

Additional objects of the invention are to be found in novel moistening mechanism which insures a proper supply of liquid to the flap of the envelope, and a simple and efficient form of feeding means, which acts to select the lowermost envelope from the stack and feed it through the apparatus.

The invention also consists in certain other features of improvement, which will be explained fully in the following description, taken in conjunction with the accompanying drawing, the novel features being pointed out in the claims at the end of the specification.

50 In the drawings:

Figure 1 is a top perspective view of an

apparatus illustrating a preferred application of the invention;

Figure 2 is a vertical sectional view taken longitudinally;

Figure 3 is a vertical sectional view taken longitudinally in another plane;

Figure 4 is a bottom plan view;

Figure 5 is a transverse vertical sectional view;

Figure 6 is a detail perspective view of a portion of the feeding mechanism;

Figure 7 is a side elevation of a portion of the apparatus, and

Figure 8 is a plan view with parts removed.

There are a number of various ways in which the novel characteristics of the invention may be adapted to practical operating structures, and the mechanism about to be described is selected merely as an example, and is not intended to limit the invention to any of the details disclosed.

The machine comprises a frame mounted upon legs A, the top of the frame which constitutes the envelope supporting means being designated by a. Mounted upon the support a is an envelope hopper comprising a fixed side wall a', and an inclined front wall a² which forms an envelope barrier, permitting the lowermost envelope to feed under it. a³ is an adjustable side wall carrying a forward extension or guide a⁴ which lies on the support a, and also a bifurcated extension a⁵ adapted to overlie the barrier a². The extension a⁵ is adjustable relatively to the barrier a², to vary the width of the envelope hopper, the extension a⁵ and the adjustable wall a³ being held in adjustable position by a suitable screw and thumb nut a⁶.

The envelope support a has an opening or cutaway portion extending substantially the length of the frame, as indicated by a⁷, and which is surrounded by an envelope supporting ledge a⁸ located within the envelope hopper, while a rod a⁹ is carried by the wall a³ and arranged oppositely to the ledge a⁸ to assist in holding the envelopes in the hopper. Arranged within the opening a⁷ is a table B occupying a position beyond the barrier a² and in the path of travel of the envelopes. When the envelopes are stacked within the

hopper, formed by the walls a' , a^2 and a^3 , they are supported by the ledge a^4 and rod a^5 , the opening a^7 allowing the flap of the lowermost envelope to extend downwardly, as will appear more clearly presently, while the table B receives the envelopes successively as they are fed through the machine, the flap of each envelope projecting beneath the table B at one side thereof to be moistened, before it is affixed to the body of the envelope. With the envelopes positioned within the hopper, the lowermost one is engaged and kicked out by a feeding means that actuates the envelope across the table B, as will now be described.

The feeding means comprises a belt C (see Figure 3), which travels on pulleys c and c' . The envelope is held in engagement with the feeding belt by means of a U-shaped yieldable track D mounted above and straddling the belt, and carried by a spring actuated arm d which is pivoted on the spindle d' . The track D has its walls curved at the forward end, as shown at d^2 , to admit a single envelope at a time and permit it to be gripped by the belt C, and the track may be otherwise formed at its front end, lying in the path of the fed-in envelope so as to admit only one envelope at a time. d^3 is a fixed abutment within the track D overlying the belt C, and acting to force an envelope against the belt, while d^4 are rollers carried by the track D and cooperating with the belt C to retain the envelope thereagainst and feed it through the machine, as the belt is caused to travel by the mechanism to be described presently. It is necessary to provide some means for automatically kicking out the lowermost envelope of the stack, or gripping it so as to bring it into feeding relationship with the belt and overlying track, and this is preferably accomplished by providing an abutment or projection on the feeding means which will act intermittently to engage the stack of envelopes and eject the bottom one of the stack. In one form, this consists of an abutment or projecting portion c^3 formed in the belt C at regular intervals. The mechanism disclosed includes a belt-groove on the pulley c , said groove having a constricted portion c^4 which cooperates with the belt C, whereby when the belt engages the constricted portion, it is forced out of its groove partially, and away from its normal position, forming the abutment or projection c^3 already referred to. The abutment c^3 engages the underside of the lowermost envelope of the stack and has a tendency to lift it upwardly and partially move it inwardly toward the table B, and after one or more operations of the abutment c^3 , the lowermost envelope is thereby carried along under the track D and is thence fed quickly through the machine by the con-

tinuous travel of the belt C. The forward end of the table B is bent slightly downwardly, as shown at b , Figure 2, in order to insure the body of the envelope going above the table, while the flap travels underneath the table. During the gripping and feeding operation of the lowermost envelope, as just described, it is essential to retain the envelopes above the lowermost one, and prevent their being fed until their regular order. This is accomplished by the action of the aforesaid track D, and its relation to the barrier a^2 and the feeding belt C. In order to assist this function of the track D, and to insure feeding of only one envelope at a time, additional means are provided for engaging the entering edges of the envelopes and preventing their movement except in successive order, and this mechanism will now be described.

A feed controlling device is provided, consisting of a guard, preferably in the form of a flexible strip of rubber or similar material, supported on the upper side of the inclined barrier a^2 , as designated at E (see Figure 2). The strip E is preferably arranged within a channel or housing e , detachably mounted on the barrier a^2 , and the lower end of the strip E is free, resting upon the table B in the path of the envelopes. Thus the flexible strip is inclined from a point above the table downwardly and thence parallel to the table, and other means can be utilized for maintaining it in this relation. The strip E is provided with a series of flexible fingers or projections, also preferably of rubber, which yieldably engage the stack of envelopes and operate to hold back all but the lowermost one of the stack. The action of the feeding means is sufficient to cause the lowermost envelope to overcome the resistance of the flexible strip E, and force under the latter. The free end of the strip E is held yieldably against the table by a weight e' carried by a pivoted arm e^2 .

The table B terminates at such a point as to afford a free space d^3 adjacent to one edge, see Figure 1, such space being for the purpose of receiving the flap of the envelope during the feed of the envelope through the machine. In order to insure passage of the flap under the table B, there is provided deflecting means lying in the path of the envelope and adapted to engage the same and bend a corner slightly downwardly, so as to produce a slight bulge in the flap, and thereby cause the flap to readily follow its proper course under the table B. The deflecting means may consist of a pivoted finger F, see Figure 1, which is curved upwardly in opposite directions, and lies at one side of the table B, the lowermost surface of the finger F being substantially flush with the under surface of the table B. The finger F

is carried by a weighted arm f , pivoted on the spindle d' . The flap of the envelope having been thus deflected to the underside of the table B , and with its gummed surface 5 uppermost, is then brought into cooperative relationship with a moistening device which will now be described.

Referring to Figures 2, 4 and 5, the moistening device preferably comprises a rotary wheel or disk G , located under the table and mounted on a spindle g , which carries a pulley g' for a purpose that will appear. The disk G is located in an inclined plane, with its upper edge located immediately under or approximately under the free edge of the table B , as shown in Figure 5. The opposite or lower edge of the disk G is positioned over a water tank H , which latter may be filled through an opening h , see 10 Figure 1. Arranged within the tank H is a water transferring member in the form of a truncated cone of cork or other similar light material, as designated by h' , the said cone being carried on an arbor h^2 which is rotatable within bearings formed in spring actuated arms h^3 . The arms h^3 tend to actuate the cone h' upwardly against the disk G , as shown in Figure 5. As the disk G is rotated, it engages and similarly rotates the cone h' , 15 which thereby continuously carries a supply of water to the under surface of the disk G , so that when the flap of the envelope is brought into engagement with the disk G , it is properly moistened.

The flap of the envelope is pressed against the disk G by suitable means, preferably in the form of spaced, spring actuated fingers I , which are mounted on the post i and are controlled by springs connected to a second post i^2 . The fingers I have their free ends bearing against the moistening disk G , and as the envelope travels across the table, the flap moves in between the fingers I and the moistening disk G , and is held with a light 20 but sufficient pressure to apply a proper amount of moisture evenly over the surface of the flap. After passing beyond the moistening disk, the flap is brought back into parallel relationship with the body of the envelope by a deflecting plate J , see Figure 2, and is then affixed to the envelope by passing between pressure rollers K and K' , the latter being mounted on spring actuating arms k which are pivoted to the rod d' .

The roller K is mounted on a spindle which carries a pinion k' , which in turn is driven by the idler k^2 , the latter being driven by the pinion k^3 , fixed on the arbor k^4 . The latter is the power spindle of the apparatus, 25 and may be operated by the hand crank k^5 or by any suitable power mechanism. The arbor k^4 also carries pulley c' already mentioned, and about which travels the belt C , thus imparting continuous motion to said

belt. The belt C engages the pulley g' , see 65 Figure 5, to operate the moistening disk G , and the belt is held against the pulley g' by a suitable belt tightener and guide l , see Figure 4.

The operation of the invention briefly described is as follows: A stack of envelopes is placed in the hopper so that their front edges follow generally the inclination of the barrier a^2 , with the flaps on the underside and located adjacent to the wall a' . Upon 70 setting the machine in motion, the feeding belt C , by means of its abutment or projection, kicks out or ejects the lowermost envelope from the stack until its front edge is engaged between the belt C and the overlying track D . In this feeding operation, the lowermost envelope passes under the lower edge of the barrier a^2 and also under the flexible fingers of the guard E resting upon the table B , the body of the envelope passing 75 between the flexible fingers of the guard and the top of the table B . The corner of the envelope is next bent downwardly by the deflecting finger F and the flap thence passes under the table B and is pressed into 80 contact with the moistening disk G , while the envelope travels across the table B . The flap is brought back to the top of the table by the deflector J , the envelope thence passing 85 between the rollers K and K' , which affix the flap tightly to the body of the envelope.

The several features of the invention herein described are not limited to the particular means set forth, but may be otherwise 100 adapted to practical purposes by modified arrangements, without departing from the underlying principles of the invention as set forth in the following claims.

We claim:

1. An envelope moistening machine comprising supporting means having an opening to receive the downwardly projecting flap of an envelope, a table located in the path of travel of the envelope, feeding means for actuating the envelope across the top of the table, deflecting means lying in the path of the envelope and acting to guide the flap to the underside of the table, and a moistening device arranged beneath the table and 110 acting to moisten the flap of the envelope as the latter is fed across the table.

2. An envelope moistening machine comprising a table, one edge of the table having a free space adjacent thereto so as to afford a space to receive the downwardly projecting flap of an envelope, feeding means for actuating an envelope across the top of the table, deflecting means located adjacent to the table and acting to bend a corner of the 120 envelope and thereby guide the flap under the table, and a moistening device arranged beneath the table and acting to moisten the 125 envelope.

flap of the envelope as the latter is fed over the table.

3. An envelope moistening machine comprising a table, feeding means for actuating an envelope across the table, deflecting means consisting of a pivoted finger located adjacent to one edge of the table and acting to bend the envelope at one corner and thereby guide the flap of the envelope under the table, and a moistening device arranged beneath the table and acting to moisten the flap of the envelope as the latter is fed across the table.

4. An envelope moistening machine comprising a table, feeding means for actuating an envelope across the top of the table, deflecting means for guiding the flap of the envelope beneath the table, a rotary moistening disk located beneath the table and inclining downwardly from one edge thereof, and means for pressing the flap upwardly against said moistening disk.

5. An envelope moistening machine comprising a table, feeding means for actuating an envelope across the top of the table, deflecting means for guiding the flap of the envelope beneath the table, a rotary moistening disk located beneath the table and inclining downwardly from one edge thereof, and a series of spaced fingers yieldably engaging the flap of the envelope and holding it against said moistening disk.

6. An envelope moistening machine comprising a table, feeding means actuating an envelope across the table, deflecting means for guiding the flap of the envelope beneath the table, a rotary moistening disk located under the table, means for pressing the flap of the envelope against said moistening disk, a water tank, and a rotary water transferring member located in the water tank

and held yieldably in engagement with said moistening disk, the water transferring member acting to carry the water from the tank to the moistening disk.

45

7. An envelope moistening machine comprising a table, feeding means actuating an envelope across the table, deflecting means for guiding the flap of the envelope beneath the table, a moistening disk located under the table and inclined downwardly from one edge of the table, means for pressing the flap of the envelope against the moistening disk, a water tank located under the moistening disk at one edge thereof, and a device 50 rotating within said tank and engaging the underside of the moistening disk.

8. An envelope moistening machine comprising a table, feeding means actuating an envelope across the table, deflecting means 60 for guiding the flap of the envelope beneath the table, a moistening device located under the table, and spaced yieldable fingers engaging the flap of the envelope and pressing it against the moistening device.

65

9. An envelope moistening machine comprising a table, feeding means actuating an envelope across the table, deflecting means for guiding the flap of the envelope beneath the table, a rotary moistening disk located 70 under the table and occupying an inclined position, the higher part of the moistening disk being in position to engage the flap of the envelope, a water tank disposed beneath the lower part of the moistening disk, and a rotary member positioned within said tank and yieldably engaging the lower edge of the moistening disk.

75

In witness whereof, we have hereunto signed our names.

WILLIAM F. SCHWEIGER.
WESLEY J. BALKWILL.
